Inventor
Ernest Frazer
by Tracy & Clegg, Atty.

UNITED STATES PATENT OFFICE.

ERNEST FRAZER, OF PORTAGE LAKE, MAINE.

ANVIL HORSESHOE VISE.

1,419,132.

Specification of Letters Patent. Patented June 13, 1922.

Application filed November 3, 1921. Serial No. 512,523.

To all whom it may concern:

Be it known that I, ERNEST FRAZER, a citizen of the United States, residing at Portage Lake, in the county of Aroostook and State 5 of Maine, have invented certain new and useful Improvements in Anvil Horseshoe Vises, of which the following is a specification.

My invention relates to vises of that class 10 which are operated by foot power and more especially to that type of vises used by blacksmiths and which are specially designed for the forming and calking of horseshoes, and also for the holding of metal for 15 the purposes of making machine bolts, and sled shoe bolts.

The objects of my invention are to provide 20 a simple, strong and quick-acting vise of this class and capable of powerful leverage and grip, and which is operated by little exertion on the part of the operator.

Another feature of my invention is to provide 25 a certain kind of vise. This vise being formed by the jaws of the tool and each of these blocks is provided with a graduated series 30 of semi-cylindrical recesses, arranged opposite each other in pairs, so that metals of different sizes may be gripped by these jaws and calks and bolts of different diameter may be formed.

To these ends the invention consists in certain novel features, which I will now proceed to describe and will then particularly point out in the claims.

35 In the drawings

Figure 1 is a side elevation,

Fig. 2 is an end elevation,

Fig. 3 is a plan view of the vise.

In the same drawings, 1 denotes the stationary side of the vise rigidly connected to the stand or bottom 15. The top of this stationary member forms one of the jaws. Pivotally connected to the side 1 at 12 is the foot-paddle 3, which operates the other jaw 2 of the vise by means of link 6 which is pivotally connected to foot-paddle 3 by pin 13 and to side 2 by pin 14. This jaw 2 is pivotally connected to 1 by pin 8. The foot-paddle 3 is provided with a recess 4 so formed as shown in Fig. 3, so as to allow the operator to easily exert his entire weight on it. Spring 5 is connected to foot-paddle 3 and base 15 and in the normal position as

shown in Fig. 1 exerts an upward pressure 55 on 3 and by means of link 6 and pivot 8 forces the jaw 2 away from contact with jaw 1. At a suitable distance above pivot 12 and forming part of member 1 there extends perpendicular to member 1 an extension or stop 7 for the purpose of limiting or gauging 60 the extent to which jaw 2 may be moved away from jaw 1.

The jaws of the tool constitute die blocks 65 being each provided with a graduated series of semi-cylindrical recesses 10 as shown in Fig. 3, arranged opposite each other in pairs. Any desired number of these pairs of recesses may be employed, and they are graduated in size so as to adapt the tool to hold and form calks of any desired shape or thickness. This is of the utmost importance, 70 so that the same jaws may be used for different sizes of calks.

The operation and advantage of this vise in practical use will be readily understood 75 by those skilled in the art.

I do not wish to be understood as limiting myself strictly to the precise details of construction hereinbefore described, and shown 80 by the accompanying drawings, as the same may be obviously modified without departing from the principle of my invention.

Having thus fully described my invention what I claim as new and desire to secure by Letters Patent is:

1. An anvil horseshoe vise of the class described comprising a stationary vertical jaw arm at the top of which and at right angles thereto and forming an integral part therewith is a stationary jaw member, a movable vertical jaw arm and a jaw member integral therewith and at right angles thereto, completing the vise by parallel contact with the stationary jaw member, and means to operate the movable jaw member comprising a 90 foot lever pivotally connected to the stationary jaw member and rotatably connected to the movable jaw member, said stationary arm being provided with an extension so as to limit the opening of the jaws. 100

2. An anvil horseshoe vise of the class described comprising a stationary vertical jaw arm at the top of which and at right angles thereto and forming an integral part therewith is a stationary jaw member, a movable vertical jaw arm and a jaw member integral 105

therewith and at right angles thereto, completing the vise by parallel contact with the stationary jaw member, both jaws of said vise being provided with semicircular apertures of various sizes, each semicircular aperture of the stationary jaw being coincident with the semicircular aperture on the movable jaw member so as to make contact with the stationary jaw member, and means to

keep the jaws apart when the machine is not in operation comprising a spring rigidly connected to the base and to the foot treadle, and so constructed that it presses up against the foot treadle, thereby causing the jaws to stay apart when not in operation. 10

15 In testimony whereof I affix my signature.

ERNEST FRAZER.
